CLAIM

The ornamental design for a single pointed knitting needle, as shown and described.

DESCRIPTION

FIG. 1 is a perspective view of the single pointed knitting needle showing my new design;

FIG. 2 is a top plan view thereof;

FIG. 3 is an enlarged front view thereof;

FIG. 4 is an enlarged rear view thereof; and,

FIG. 5 is an enlarged cross sectional view taken on line 5-5 of FIG. 2.

The broken lines in FIGS. 1-5 are for the purposes of illustrating environment only and form no part of the claimed design.

1 Claim, 3 Drawing Sheets(56)
